UNITED STATES PATENT OFFICE

ALFRED HUSTER, OF KIEL, GERMANY, ASSIGNOR TO FRIED. KRUPP GERMANIAWERFT
AKTIENGESELLSCHAFT, OF KIEL-GAARDEN, GERMANY

WATER TUBE BOILER

Application filed July 30, 1929, Serial No. 382,148, and in Germany August 3, 1928.

The invention relates to water tube boilers and more particularly has reference to a tight tube wall intended for boilers of this class and composed of a plurality of rows of tubes.

As well-known, tight tube walls of this type are formed from two or more rows of tubes by bending these tubes on a portion of their length into a common plane. When a passage for the combustion gases is provided at the end of the tight tube wall, the latter is resolved again on a corresponding portion so as to form anew the original rows of tubes. Owing to the tight wall subsiding into these spaced rows of tubes at acute angles and due to the small pitch of these rows, deposit of flue dust in front of the passage for the combustion gases is favored. This passage therefore will easily become choked up by deposits of flue dust and clinker to such an extent that interruption of service occurs. This drawback is avoided by the invention.

To this end the invention consists in the fact that the tight tube wall which is formed by assembling two or more rows of tubes, in the range of the passage for the combustion gases is resolved into a number of rows of spaced tubes which is at least by one row greater than the rows the wall is originally composed of, at least the two first of these spaced rows having a larger pitch than the original rows. The tubes forming the original solid wall are separated unequally. One fourth of the tubes are bent to form the outermost row, one fourth to form the second row and one half to form the third row, each row behind the other. Thus the pitch or distance between the tubes of the first two rows is greater than that between the tubes of each of the original two rows that start out from the upper drum. Where protective tubes are provided which project beyond the tight tube wall, they are arranged according to the invention so as to be situated each in front of the individual tubes of the first row of the spaced tubes forming the passage.

In order that the invention can be more readily understood, an embodiment of the same is illustrated by way of example in the drawings in which

Figure 1 is a vertical section through a

water tube boiler designed according to the invention, and

Figures 2 to 4 are horizontal sections, seen from the top, on the lines 2-2, 3-3, 4-4, respectively, of Figure 1.

Referring to these figures, A denotes the tight tube wall which is formed by two rows B and C of vertical tubes. Combustion gases pass from a combustion chamber E through the tight tube wall A at D where the latter is resolved. According to the invention the tube wall is resolved here so as to form three rows of tubes F, G, H, the two former having a considerably larger pitch than the original rows B and C. The formation of ridging deposits of solidifying liquid or pasty flue dust is avoided by this arrangement. For, previous to reaching the row of tubes H on its way between the largely pitched rows of tubes F and G, the flue dust has already become solid and therefore is no longer able to stick. By a comparison of Figs. 2 and 4, it is seen that the row H is composed of the tubes of original row C, whereas the rows F and G are formed by the alternate tubes of original row B.

K denotes protective tubes arranged in front of tube wall A the pitch of which tubes is so chosen that they are situated just in front of the individual tubes of the row F. Due to this arrangement they do not narrow the passage areas but notably contribute to a rapid cooling of the flue dust particles. L denotes the tubes of the first row of vertical tubes behind the tight tube wall A.

The location of the tight tube wall itself and that of the passage for the gases within this tube wall may be determined as desired.

What I claim, is:

1. A water tube boiler having a tight tube wall composed of at least two rows of tubes and having a passage for the combustion gases, said passage being formed by spacing portions of the tubes of said tight tube wall so as to form a number of open rows of tubes which is greater than the number of rows the wall is originally composed of, the first of these open rows of tubes having a larger pitch than one of the remaining rows.

2. A water tube boiler having a tight tube

100

- wall composed of at least two rows of tubes and having a passage for the combustion gases, said passage being formed by spacing portions of the tubes of said tight tube wall so as to form a number of open rows of tubes which is greater than the number of rows the wall is originally composed of, at least the two first of these open rows of tubes having a larger pitch than the remaining ones.
- 10 3. A water tube boiler having a tight tube wall composed of at least two rows of tubes and having a passage for the combustion gases, said passage being formed by spacing portions of the tubes of said tight tube wall so as to form a number of open rows of tubes which is greater than the number of rows the wall is originally composed of, protective tubes arranged in front of said tube wall and situated in the range of said passage just in front of the tubes of the first of said open rows of tubes.
4. A water tube boiler having a tight tube wall composed of at least two rows of tubes and having a passage for the combustion gases, said passage being formed by spacing portions of the tubes of said tight tube wall so as to form a number of open rows of tubes which is greater than the number of rows the wall is originally composed of, protective tubes arranged in front of said tube wall and situated in the range of said passage just in front of the tubes of the first of said open rows of tubes, at least the two first of these open rows of tubes having a larger pitch than the remaining ones.
5. A water tube boiler having a tight tube wall composed of two rows of tubes in alternately adjacent relationship, and having a passage for the combustion gases, said passage being formed by spacing portions of the tubes of said tight tube wall so as to form three open rows, the first two of these being formed from one of the first said rows of tubes and each of the first two rows of tubes being formed of alternate tubes of the said row.
- 40 45 The foregoing specification signed at Hamburg, Germany, this 15th day of July, 1929.
